UNITED STATES PATENT OFFICE.

EDWARD E. HALPEN, OF LOS ANGELES, CALIFORNIA, ASSIGNOR OF ONE-HALF TO
A. GRANT WEISER, OF LOS ANGELES, CALIFORNIA.

LOCK.

1,367,698.

Specification of Letters Patent.

Patented Feb. 8, 1921.

Application filed October 15, 1919. Serial No. 330,691.

To all whom it may concern:

Be it known that I, EDWARD E. HALPEN, a citizen of the United States, residing at Los Angeles, in the county of Los Angeles, State 5 of California, have invented new and useful Improvements in Locks, of which the following is a specification.

This invention relates to locks and particularly to locks such as are used on doors 10 of various kinds. It is an object of the invention to provide a simple and effective door lock having a single bolt with manually operated means on the inside and key operated means on the outside for dogging or 15 positively locking the bolt.

A particular feature of the invention is the simple and inexpensive construction which is employed in the lock. The mechanism by which the lock bolt is positively 20 locked is particularly simple and effective. When the positive locking means is set or thrown so as to lock the bolt the bolt is rigidly and solidly held in the lock position and is not dependent upon a spring or any 25 resilient means.

Further objects and features of the invention will be readily understood from the following detailed description of a typical embodiment of the invention throughout 30 which reference is had to the accompanying drawings is which—

Figure 1 is an interior face view of my improved lock showing the positive locking mechanism in the released position; Fig. 2 35 is a view similar to Fig. 1 showing the positive locking mechanism in the set or lock position; Fig. 3 is a section taken as indicated by line 3—3 on Fig. 1; and Fig. 4 is a section taken as indicated by line 4—4 on 40 Fig. 1.

Throughout the drawings numeral 10 designates the mechanism casing which may be of the type commonly used in locks of this character. The latch bolt 11 is preferably of the type commonly used in door locks and is carried in an aperture 12 in the front wall of the case 10. The inner portion of the bolt 11 forms a shoulder 13 from which a guide rod 14 extends inwardly in 45 the casing 10. The rod 14 is carried or guided by a lug or projection 15 which extends into the casing 10 from one of its walls. A suitable spring 16 is provided in connection with the rod 14 between the 50 shoulder 13 and the lug 15 to normally keep

the bolt 11 in the out position, as shown in the drawings. The lock is provided with a block 17 which is adapted to be moved by a lever 18 one end of which extends from the front of the door and is adapted to be moved or operated manually. An ordinary type of swivel 19 is also provided in the lock into which a rod 20 extends from a knob on the inside of the door. An arm 21 is pivotally mounted at 22 in the casing 10 and is arranged so as to engage the tail piece 23 which is mounted on the end of rod 14. The arm 21 is provided with a suitable projection 24 which engages the block 17 and a lug 25 extends from the swivel 19 so as to engage the arm 21, as clearly shown in the drawings. Upward movement of the block 17 (caused by the movement of lever 18) or rotation of swivel 19 in the direction indicated by the arrow in Fig. 1, will cause 65 movement of the arm 21 in the direction indicated by the arrow in Fig. 1, and due to the engagement of the tail piece 23 by the arm 21 will cause withdrawal or drawing in of the bolt 11. Operation of the inside knob 70 or the swivel 19 will always cause withdrawal of the bolt 11, unless the bolt is positively locked as will be hereinafter explained, and the operation of the lever 18 will always cause withdrawal of the bolt 75 unless the pin 26 is in position to engage lug 27 which extends from block 17 as shown in Fig. 2. The pin 26 is out of engagement with the lug 27 when it is in the position shown in Fig. 1 and it is moved to this position by moving pin 28 from the position shown in Fig. 2 to the position shown in 80 Fig. 1. The pins 26 and 28 are connected by a connecting link 29. The mechanism so far described is the ordinary type commonly 85 used in locks of this general character and it will be understood that the invention is not in any way limited to such a form of mechanism but may be advantageously arranged in connection with various other 90 mechanisms.

From the above description it will be understood how the bolt 11 is locked in the out position when the pin 26 is in engagement with the lug 27 and that it can not be 95 withdrawn by movement of the lever 18 although it can be opened or moved by movement of the swivel 19. Although the mechanism for withdrawing the bolt 11 by movement of lever 18 can be positively locked by 100

pin 26 the bolt itself is entirely dependent upon spring 16 to hold or keep it in the out or locking position. A door locked in this manner is secure enough for certain situations but it is not secure enough for circumstances or conditions which demand that the door be firmly and positively locked.

A dog 30 having arms 31 and 32 is pivotally mounted on a pin 33 which is carried 10 by the casing 10. The dog 30 is so shaped and arranged that when the bolt 11 is in the out or lock position it can be moved or thrown so that the arm 31 engages the shoulder 13 of the bolt and the arm 32 engages the lug 15 which extends from the casing 10. When the dog is in this position it will be readily understood how it 15 positively and firmly holds the bolt 11 in the out position and that the bolt is no longer dependent upon the spring 16 to hold it in the locked position. When the dog 30 is between the shoulder 13 and the lug 15 any pressure on the bolt tending to push it in is directly transmitted to the stationary 20 lug 15. Fig. 2 shows the dog in position to positively lock the bolt 11 while Fig. 1 shows it moved or thrown to a position where it does not engage the bolt and does not interfere with its movement or action in any way. 25 The dog 30 may be moved or controlled from the inside of the door by a thumb turn or small knob 40 which is arranged in connection with a swivel 41. An arm 42 extends from the swivel 41 and is connected 30 to the dog 30 by means of connecting rod 43. The connecting rod 43 is pivotally connected to a pin 44 which extends from the dog 30 and has a pin 45 extending from it on which is pivotally carried the arm 42. 35 The various connections throughout the mechanism and particularly the connection between the arm 42 and the pivot pin 45 are made comparatively loose to prevent binding or sticking of the parts when the mechanism is being operated. The connecting rod 43 is provided with a projection 50 which is adapted to engage the tail piece 23 so that rotation of the knob 40 to cause movement of the connecting rod 45 in the direction indicated by the arrow in Fig. 1 will cause the bolt 11 to be withdrawn into the casing 10. The dog 30 may be moved or operated from the outside of the door by rotating a block 60, which is 55 carried in a drum 61, when a suitable key 62 is placed in the block 60 so as to cause tumblers 63, which are in the drums 61, to be in position to release the block 60. This particular locking mechanism is merely 60 typical and it will be understood that any suitable locking mechanism could be advantageously used in this connection. An arm 65 extends from block 60 and engages pin 45 on either side to cause movement of 65 the pin in either direction. In this pur-

pose the block 60 and arm 65 are rotatable through a whole revolution, as is common to such locks. Arm 65 will thus, when operated by lug 62, cause exactly the same movements as are caused by the turning of member 40. In order to hold the dog 30 in the locking position and prevent it from being moved by jarring or vibration a suitable spring 70 is arranged in connection 70 with the arm 32 of the dog, as clearly shown in Figs. 1 and 2. It will be particularly noted in the drawings that the spring 70 is arranged in the casing so as to engage the projection 15 when the dog is out of engagement with the bolt and that it does 75 not interfere in any way with the withdrawal or retraction of the bolt.

Having described a typical embodiment of the invention I do not wish to limit myself to the particular details herein above 80 set forth but wish to reserve to myself any changes or variations that may appear to those skilled in the art or fall within the scope of the following claims.

Having described a preferred form of my 90 invention, I claim:

1. In a lock of the character described, a casing having a projection, a latch bolt carried by the casing, and manually operated means for positively locking the bolt, 95 said means embodying a pivoted member adapted to be thrown into engagement with the bolt and the projection so that pressure on the bolt is transmitted directly to the projection through the pivoted member. 100

2. In a lock of the character described, a casing having a projection, a latch bolt carried by the casing, manually operated means for positively locking the bolt, said means embodying a pivoted member adapted to be thrown into engagement with the bolt and the projection so that pressure on the bolt is transmitted directly to the projection through the pivoted member, and means for holding the pivoted member in 105 engagement with the bolt and projection. 110

3. In a lock of the character described, a casing having a projection, a latch bolt carried by the casing, and manually operated means for positively locking the bolt, 115 said means embodying, a pivoted member adapted to be thrown into engagement with the bolt and the projection so that pressure on the bolt is transmitted directly to the projection through the pivoted member, and a link in connection with the pivoted member, the link being adapted to be moved so as to cause throwing of the pivoted member. 120

4. In a lock of the character described, a casing having a projection, a latch bolt carried by the casing, and manually operated means for positively locking the bolt, said means embodying, a pivoted member adapted to be thrown into engagement with the bolt and the projection so that pressure on 125 the bolt and the projection so that pressure on 130

the bolt is transmitted directly to the projection through the pivoted member, and a link in connection with the pivoted member, the link being adapted to be moved so as to cause throwing of the pivoted member, and means for holding the positive locking means in the locked position, said means embodying a spring arranged in connection with the pivotal member.

10 5. In a lock of the character described, a casing having a projection, a latch bolt carried by the casing, and manually operated means for positively locking the bolt, said means embodying, a pivoted member adapted to be thrown into engagement with the bolt and the projection so that pressure on the bolt is transmitted directly to the projection through the pivoted member, and an operating link in connection with the pivoted member, and means on the link arranged in relation with the bolt so that it can be moved to cause withdrawal of the bolt.

6. In a lock of the character described, a 25 casing having a projection, a latch bolt carried by the casing, the bolt having an extended portion, and manually operated means for positively locking the bolt, said means embodying, a pivoted member adapted to be thrown into engagement with the bolt and the projection so that pressure on the bolt is transmitted directly to the projection through the pivoted member, and a link in connection with the pivoted member, 30 the link being adapted to be moved to cause throwing of the pivoted member, the link being arranged in connection with the extended portion of the bolt so that it can be moved to cause withdrawal of the bolt.

40 7. In a lock, the combination of a case, a spring projected latch bolt, knob operated means on one side of the case to retract the bolt, a thumb latch means on the other side of the case to retract the bolt; and means 45 operated by a key on said last mentioned side of the lock and by a thumb turn on the other side of the lock to retract the bolt or to positively lock the bolt in the projected position, said last mentioned means comprising a dog adapted to be thrown into engagement with the bolt to positively lock the bolt, and a member in connection with the dog adapted to be moved into engage-

ment with the bolt to withdraw it when the dog is out of engagement with the bolt, and 55 means for holding the dog in engagement with the bolt, said means comprising a spring adapted to engage and hold the dog only when it is in engagement with the bolt.

8. In a lock, the combination of a case, a 60 spring projected latch bolt, knob operated means on one side of the case to retract the bolt, a thumb latch means on the other side of the case to retract the bolt; and means operated by a key on said last mentioned 65 side of the lock and by a thumb turn on the other side of the lock to retract the bolt or to positively lock the bolt in the projected position, said last mentioned means comprising a pivoted dog adapted to be thrown into 70 engagement with the bolt to positively lock the bolt, and a link pivotally connected to the dog adapted to throw the dog into engagement with the bolt and be moved into engagement with the bolt to withdraw it, 75 the link being adapted to be moved by the key or the thumb turn.

9. In a lock of the character described, a casing, a latch bolt therein, means for operating and for positively locking said bolt 80 embodying a pivoted dog adapted to be thrown behind the bolt, a link pivoted at one end to the dog, a projection on the bolt, and means to move the other end of the link against said projection whereby to operate 85 the dog and to withdraw the bolt by movement of said link.

10. In a lock of the character described, a casing, a latch bolt therein, means for operating and for positively locking said bolt 90 embodying a pivoted dog adapted to be thrown behind the bolt, a link pivoted at one end to the dog, a projection on the bolt, means to move the other end of the link against said projection whereby to operate 95 the dog and to withdraw the bolt by movement of said link; and yielding detent means engaging the dog to hold it in its bolt dogging position and engaging the dog only when in that position.

100 In witness that I claim the foregoing I have hereunto subscribed my name this 1st day of October, 1919.

EDWARD E. HALPEN.

Witness:

VIRGINIA I. BERINGER.
